[57] **CLAIM**

The ornamental design for an adjustable boating chair pedestal, as shown and described.

DESCRIPTION

FIG. 1 is a left side elevational view of an adjustable boating chair pedestal showing my new design;

FIG. 2 is a front elevational view thereof;

FIG. 3 is a top plan view thereof;

FIG. 4 is a right side elevational view thereof; and

FIG. 5 is a rear elevational view thereof.

The chair portion shown in broken lines is to illustrate use of the instant design and forms no part of the invention.

FIG. 1

FIG. 2

FIG. 3

FIG. 4

FIG. 5
